Filed Apr. 8, 1959, Ser. No. 804,964

2 Claims. (Cl. 239—17)

This invention relates generally to display fountains, and embraces certain unique and highly advantageous structural features thereof.

It is one object of the present invention to provide a display fountain which is particularly well adapted to be moved from place to place, being extremely light in weight and quickly and easily disassembled and reassembled without any special skill or great effort.

It is another object of the present invention to provide a display fountain of the type described which is extremely simple in construction, entirely reliable and fool-proof in operation, and which is durable in use over long-sustained periods, having an extremely long useful life.

It is a more particular object of the present invention to provide a unique fountain construction which tends to be self-leveling, even when supported on a floor or ground surface which is out of level, all without the use of special leveling devices.

It is still a further object of the present invention to provide a highly advantageous arrangement of fluid conduits whereby substantially equal fluid pressures are produced at all discharge openings, all without the interpolation of dead ends or undue constriction in the fluid path for an extremely high efficiency of fluid motion.

It is still a further object of the present invention to provide a fountain having the advantageous characteristics mentioned in the preceding paragraphs, which employs an extremely simple and efficient combination and arrangement of parts, and which can be economically manufactured for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Figure 1 is a top perspective view illustrating a fountain of the present invention in operative condition;

Figure 2 is a top plan view of the fountain of Figure 1, somewhat enlarged for clarity of detail;

Figure 3 is a sectional view taken substantially along the line 3—3 of Figure 2;

Figure 4 is a partial sectional view taken substantially along the line 4—4 of Figure 2; and

Figure 5 is a partial sectional view taken substantially along the line 5—5 of Figure 3.

Referring now more particularly to the drawings, and specifically to Figure 1 thereof, the fountain illustrated therein is generally designated 10, and includes a supporting pedestal or stand 11 adapted to rest on a suitable floor or ground surface. Carried by the pedestal 11 is a basin, pan, or vessel 12 which carries the fountain-producing apparatus 13.

The pedestal 11 is of generally annular, centrally open

2

configuration, including a normally horizontally disposed, circular rim or ring 15 from which fixedly depend a plurality of legs 16 for engagement with a ground surface or floor 17. Thus, the upper pedestal ring 15 bounds a generally annular opening serving a purpose appearing presently.

The shallow vessel, pan, or basin 12 may be of circular-outline configuration, as illustrated, and is formed with a bottom wall 19 having an upstanding peripheral margin 20 defining a side wall. The central region of the basin bottom wall 19 is depressed to form a downward protuberance 21 on the underside of the basin, which protuberance defines a central, upwardly opening well 22 on the upper side of the basin. That is, the depressed central portion of the basin 12 defines a convex depending protuberance on its underside, and a concave depression or well on its upper side. As best seen in Figure 3, the basin 12 seats on the pedestal 11 with the protuberance 21 of the well 22 depending partially through the pedestal ring 15, with the latter being in supporting engagement with the under, external surface of the well 22 to support the basin spaced above the ground surface 17. Obviously, the basin 12 is adapted to be inclined slightly in any desired direction relative to the supporting pedestal ring 15 in the manner of a ball-and-socket joint. Conversely, the basin is therefore adapted to be disposed level irrespective of the out-of-level condition of the supporting pedestal 11. As will appear more fully hereinafter, this advantageous structure enables the basin to be self-leveling to a substantial extent, even under adverse conditions of vibration and shock. If desired, frictional members or rubber rings 24 may be secured at spaced locations to the pedestal ring 15 for frictional engagement with the supported basin 12.

The spray-or fountain-producing apparatus 13 includes an annular fluid conduit or tube 26 of generally circular configuration and defining an endless fluid path. The annular tube or conduit 26 is of a size adapted to seat in the basin 12 extending about an upper region of the well 22. Provided at preferably equally, circumferentially spaced locations about the annular tube 26, in the upper side thereof, are a plurality of upstanding discharge nozzles or orifices 27, which may advantageously be inclined slightly inward toward the center of the annular conduit.

Extending diametrically across the generally horizontally disposed annular conduit 26 is a cross tube or conduit 28 which has its opposite ends joined to diametrically opposed regions of the annular conduit, as by fittings 29, for fluid communication with said annular conduit at said diametrically opposed locations. Thus, the cross tube 28 is substantially coplanar with the annular conduit or circular tube 26.

A circulating pump, such as the pump illustrated at 31, may be seated in a lower region of the well 22, spaced below the annular conduit 26 and the cross tube 28. The pump 31 may be of a submersible type, electrically operated, as by a supply conductor 32 passing outward through an appropriate, sealed opening in the basin. A pump inlet is generally designated 33, and a mesh strainer or filter 34 is preferably secured over the inlet to prevent the passage of dirt into the pump. The filter 34 may assume the configuration of a reticulated tube having one end closed and one end open, the latter end being connected to the inlet 33 of the pump 31. Extending upward from the outlet of the pump 31 is a connecting tube 35 which has its upper end connected, as by a tee fitting 36, to a medial region of the cross tube 28. A manually operable valve 37 may be connected in the connecting tube 35 to control the rate of liquid flow from the pump through the latter tube.

It will now be appreciated that a recirculating-fluid sys-

tem is defined through the pump 31 which passes liquid upward through the connecting tube 35, thence in both directions through the cross tube 28 to the diametrically opposed regions 29 of the annular tube 26. In the annular tube 26, liquid passes in opposite directions away from each of the regions 29 toward the opposite region 29. Of course, liquid passing along the annular tube 26 discharges upwardly from the nozzles 27. As there are no constrictions, dead ends, or other serious inefficiencies in the transmission of liquid, a relatively high efficiency of liquid transmission is obtained, thereby enabling the use of a relatively small pump. Further, as the system is entirely symmetrical, with equal rates of flow through the opposite annular-tube regions 29, it is obvious that a symmetrical pattern of fluid pressure is achieved at the various discharge orifices 27. Moreover, as would be expected, discharge pressure decreases slightly in the directions away from the regions 29, but such decrease is negligible, and compensated for by the reinforcing effect of meeting streams at the tube regions spaced 90° from the regions 29. Hence, a substantially uniform and constant orifice discharge pressure is achieved all along the annular tube 26.

Of course, liquid discharged from the nozzles 27 passes upward to achieve its desired ornamental effect, and returns by gravity to the well 22, as at 40. From the well, the liquid is again recirculated, entering the pump 31 through the inlet filter or strainer 34.

A protective cover 41 of reticulated sheet material or screening extends across the upper region of the well 22, within the area encompassed by the annular conduit 26, to hide the apparatus within the well, as well as to prevent foreign matter from entering the well. The reticulated cover 41 passes over the cross tube 28, and is provided with a peripherally extending depending skirt 42 having its lower edge in seating engagement with the inner surface of the basin 12. Further, the skirt 42 may be provided with a pair of diametrically opposed cutouts 43 opening downward through the lower skirt edge, for respectively receiving opposite end portions of the cross tube. In this manner, the protective covering 41 is firmly retained in position, and freely removable, as desired.

An annular upstanding wall 45 extends closely about the exterior of the annular conduit 26, having its lower edge resting on the basin, and extending upward to protectively surround the nozzles 27. The annular wall 45 is freely removable, when desired, and replaceable in its surrounding relationship with the annular tube 26 to protect the nozzles 27 from foreign articles in the basin.

As a reservoir of liquid 40 collects in the well 22 for recirculation through the fluid-conduit system, it is apparent that a substantial weight retains the basin 12 in position on the pedestal 11. Further, as the weight within the well depends vertically downward, and as the basin is slightly tiltable relative to the pedestal, as described hereinbefore, it will be understood that the basin tends to be self-leveling when liquid is contained in the well, and even if the pedestal is out of level.

From the foregoing, it is seen that the present invention provides a display fountain which fully accomplishes

its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. A display fountain comprising a support pedestal, a basin carried by said pedestal and having a depressed portion for collecting liquid, a generally circular endless fluid conduit in said basin extending about said depressed portion and having circumferentially spaced upwardly opening discharge orifices, a diametrically extending fluid conduit having its ends connected to opposed regions of said circular conduit, a pump in said depressed portion below said circular conduit, fluid-communication means connected between said pump and a medial region of said diametral conduit for pumping liquid from said depressed portion to said fluid conduits for discharge therefrom at substantially equal pressure thereabout, said support pedestal being generally circular in configuration and circumscribing an opening receiving said depressed basin portion, said basin portion being of generally circular horizontal cross section at all points, said depressed basin portion defining on its underside a convex protuberance depending through said pedestal opening and conformably seated in bearing engagement on the pedestal portion bounding said opening, the weight of liquid in said depressed portion tending to level said basin even when said pedestal is out of level, a reticulated cover extending across the upper region of said depending portion within said circular conduit and over said diametral conduit, and a skirt depending from the periphery of said cover into seating engagement with said basin, said skirt being provided with a pair of downwardly opening cutouts respectively receiving opposite end portions of said diametral conduit.
2. A display fountain comprising a circular horizontal support pedestal, a basin of circular horizontal cross section at all points having a centrally depressed well and seated on said pedestal with said well depending partially into said pedestal, an endless circular fluid conduit seated in said basin extending about said well and having circumferentially spaced upwardly opening discharge orifices, a pump located in said well below said circular fluid conduit, fluid-conducting means communicating between said pump and circular conduit, said basin being horizontally self-seating in said pedestal, a reticulated cover of circular-outline configuration extending across said well within said circular conduit, and a skirt depending from the periphery of said cover into horizontal self-seating engagement with said basin.
